ATTORNEY

UNITED STATES PATENT OFFICE

2,057,224

BRASSIÈRE

Lucile Bradshaw Barley, Harlingen, Tex.

Application August 20, 1935, Serial No. 37,075

2 Claims. (Cl. 2—42)

This invention relates to brassières and has for the primary object the provision of a supporting means which will operate in connection with any type or form of breast engaging elements or pockets and will retain the latter in proper position during all movements of the wearer and permit the wearer to have freedom of movement and comfort and is so constructed that backless outer garments may be worn without exposing to view said supporting means, the latter preventing the pockets from riding up on the person.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a fragmentary perspective view showing my invention applied to a person.

Figure 2 is a fragmentary perspective view showing the rear of my invention and as applied to a person.

Figure 3 is a plan view showing the supporting means and its connection with the breast pockets.

Figure 4 is a fragmentary rear elevation showing a modified form of my invention.

Referring in detail to the drawing, the numeral 1 indicates breast pockets of a brassière. These pockets may be of any desired shape and construction and made from any material suitable for the purpose. The pockets 1 have connected thereto my invention consisting of a gusset 2 forming a permanent connection between the pockets and adapted to lie between the breasts of a wearer with the pockets fitting the breasts. The gusset 2 is extended to form an attaching strap 3 secured to a waist encircling strap 4. The strap 3 of the gusset 2 is secured to the waist encircling strap 4 intermediate the ends of the latter. Any suitable securing means 5 may be employed for fastening together the ends of the waist encircling strap. Shoulder straps 6 are attached to the upper edges of the pockets and to the waist encircling straps 4 adjacent the ends thereof so that when the brassière is applied to a person the shoulder straps pass over the shoulders and are spaced a considerable distance from the spine of the wearer leaving the back of the person exposed to the waistline so that backless garments can be worn without the shoulder straps showing.

Retaining straps 7 are secured to the gusset 2 and to the lower edges of the pockets 1 and to the shoulder straps 6, as shown at 8. The straps 7 when the device is worn by a person pass under the arms at a considerable distance below the armpits and instead of attaching to the shoulder straps, as at 8, they may be attached to the waist encircling strap or band 4 where the shoulder straps join thereto and as shown at 9 in Figure 4. The straps 7 cooperate with the strap 3 of the gusset 2 in causing the pockets to snugly fit the breasts and will prevent the pockets from riding up during movements of the person. The gusset 2 being connected to the waist strap 4 creates a downward pull on the pockets while the straps 7 being connected to the shoulder straps 6, as at 8, or as at 9, to the waist strap, lateral pulls will be made on the pockets 1 causing the pockets to remain in position on the breasts with the gusset 2 tightly pulled inwardly between the breasts.

The straps referred to and the gusset may be constructed of elastic material, semi-elastic material, of a knitted formation or any other material suitable for the purpose.

Having described the invention, I claim:

1. A brassière comprising breast pockets, a gusset connecting said pockets, shoulder straps secured to the pockets and adapted to pass over the shoulders of a person and be spaced a maximum distance from the spine of a person to expose a maximum portion of the back of a person, a waist encircling strap having the shoulder straps connected thereto with the connections between the waist encircling strap and the shoulder straps located on the back of the person and adjacent to the waist line of said person, said gusset having an extended portion secured to the waist encircling strap at the front of a person to prevent the pockets from moving upwardly on the person, straps secured to the pockets and to the gusset and to the shoulder straps at the rear of the person and passing under the arms of the person at a maximum distance from the armpits of the person and cooperating with the extended portion of the gusset in preventing upward movements of the pockets and exerting a lateral pull upon the gusset to cause the latter to tightly fit the person between the breasts.

2. A brassière comprising breast pockets, a gusset connecting said pockets, shoulder straps secured to the pockets and adapted to pass over the shoulders of a person and be spaced a maxi-

mum distance from the spine of a person to expose a maximum portion of the back of a person, a waist encircling strap having the shoulder straps connected thereto with the connections 5 between the waist encircling strap and the shoulder straps located on the back of the person and adjacent to the waist line of said person, said gusset having an extended portion secured to the waist encircling strap at the front 10 of a person to prevent the pockets from moving

upwardly on the person, oppositely extending straps secured to the gusset and to the lower edges of the pockets and connected to the waist encircling strap at the back of the person where the shoulder straps connect to the waist encircling strap to exert a downward and lateral pull on the pockets and on the gusset to cause the latter to fit tightly against the person between the breasts. 5

LUCILE BRADSHAW BARLEY. 10
